APPARATUS FOR COUNTING AND BANDING ENVELOPES AND THE LIKE

Richard Winkler, Rengsdorf, near Neuwied, and Kurt Dunnebier, Wollendorf, near Neuwied, Germany, assignors to Berkley Machine Company, Kansas City, Mo., a corporation of Missouri

Application August 20, 1956, Serial No. 604,878

Claims priority, application Germany September 26, 1955

9 Claims. (Cl. 53—198)

This invention relates to machines for making envelopes and similar articles, and more particularly to an apparatus in association with such machines for automatically counting and packeting such envelopes or similar articles.

Heretofore it has been the practice to provide such machines with counting devices whereby the envelopes may be counted and separated into groups, or the envelopes are counted by hand, after which the groups to be formed into packets are introduced into a separate wrapping machine, all of which requires a considerable amount of time and labor and there is possibility of error so that the proper number of envelopes are not included in each packet.

Another difficulty is that modern high speed envelope making machines are capable of a very high output, but when the envelopes are to be packeted the output must be limited in coordination with the present comparatively slow methods of counting and packeting the envelopes. If additional operators and wrapping machines are employed to keep up with the normal capacity of the envelope making machine, the labor cost and investment overcome the advantage gained by the high speed machines.

It is therefore the principal object of the present invention to provide counting and packeting mechanism which is adapted to count and packet automatically the output of modern envelope machines.

Other objects of the invention are to provide for automatically depositing envelopes in timed relation within traveling pockets to assure the desired number of envelopes in each pocket; to provide automatic removal of the envelopes from each pocket and banding them together with a wrapping strip; to provide for automatically detecting packets containing less than the required number of envelopes; to provide the traveling pockets with flexible elements arranged to be spread apart for facilitating insertion of the envelopes and to close suddenly on the envelopes when a given number has been deposited so as to divert the next envelope into the following pocket; to provide pockets that are readily adjustable to accommodate any desired number of envelopes; and to provide elevating means for lifting the envelopes from the pockets and carrying them through the wrapping stations to a delivery table.

Other objects of the invention are to provide means for feeding the wrapping strip from a roll, cutting off the required length, extending it around a packet, and sealing the ends of the strip together.

In accomplishing these and other objects of the invention, as hereinafter pointed out, we have provided improved structure, the preferred form of which is illustrated in the accompanying drawings wherein:

Fig. 1 is a longitudinal section through an apparatus constructed in accordance with the present invention for receiving the envelopes from an envelope making machine, assembling the envelopes into groups each contain-

2

ing a given number, wrapping each group into a packet and delivering the packets for boxing.

Fig. 1A shows a portion of the apparatus of a type for feeding the envelopes from a stack after they have been removed from the delivery end of an envelope making machine.

Fig. 2 illustrates diagrammatically a detector mechanism for indicating and/or discarding a packet having less than a proper number of envelopes.

10 Fig. 2A is a side elevational view of the detector.

Fig. 3 is an enlarged longitudinal section of the pocket filling mechanism, and showing a pocket in open position to receive envelopes one at a time from a feed wheel.

15 Fig. 4 is a similar view but showing the pocket snapped closed and containing a group of envelopes to form a given size packet.

Fig. 5 is a fragmentary plan view of the conveyer mechanism particularly illustrating the arrangement of the resilient elements which form the front and rear walls of a pocket.

20 Fig. 6 is an enlarged vertical section of the delivery end of the pocket conveyer, the lower end of the packet elevator, and the mechanism for applying a wrapping band.

Fig. 7 is a similar section showing a strip being wrapped 25 about a packet of envelopes as they are lifted by the packet elevator.

Fig. 8 is a section similar to Fig. 6 and showing the parts in position for gumming the wrapping strip.

30 Fig. 9 is a similar section showing movement of the gummed end of the strip into sealing contact with the opposite end.

Referring more in detail to the drawings:

1 illustrates an envelope packeting mechanism constructed in accordance with the present invention for receiving completed envelopes from off the delivery rollers 2 of a modern high speed envelope making machine. The mechanism 1 includes spaced apart side frames 3 for carrying therebetween the various operating parts, which generally include a conveyer 4 for feeding the envelopes to a rotor 5 for depositing the envelopes into a pocket conveyer 6 for delivery to an elevator 7 which in turn removes the envelopes from the pocket conveyer 6 and conveys them through a strip 45 wrapping mechanism 8 and a drier 9 for discharge onto an offtake conveyer 10.

The conveyer 4 includes an endless belt 11 operating over rollers 12, 13 and 14, that are suitably carried between the side frames 3 and continuously operated 50 in the direction of the arrow. The rollers 12 and 13 carry the upper run of the conveyer belt in aligning registry with the path of travel of the envelopes fed by the rollers 2 to carry the envelopes to a roller 15 which cooperates with pressure rollers 16 to feed the envelopes 55 onto the rotor 5. Suitable pressure rollers 17 and 18 are also used to cooperate with the upper run of the conveyer belt for assuring forward movement of the envelopes in successive order.

The rotor 5 is carried on a shaft 19 that is continuously 60 driven in timed relation with the conveyer 4 for depositing envelopes one at a time into an open pocket of the pocket conveyer 6, as later described.

The pocket conveyer 6 includes spaced apart transverse shafts 20 and 21 that are rotatably carried by the side 65 frames 3, with the shaft 20 being located below the rotor 5 and the shaft 21 at a lower level and spaced forwardly therefrom, as shown in Fig. 1. Adjustably mounted on each of the shafts 20 and 21 are two pairs of sprockets 22 and 23 carrying two pairs of parallel chains 24—25 and 70 24'—25'. Pivotedly mounted on the chains 24 and 24' of each pair are rocking holders 26, and fixed to selected links of the chains 25—25' are fixed holders 27. Fixed to

the rocking and fixed holders are flexible elements 28 and 29 forming the front and rear walls of pockets 30. The pairs of sprockets are spaced on their shafts so that the spring elements 28 and 29 of one pair of chains cooperate with the spring elements 28 and 29 of the other pair of chains to hold the envelopes at both sides of their center lines, with the ends of the envelopes projecting outwardly therefrom.

The sprockets carrying the chains 24 and 25 are positioned radially on their supporting shafts, so that the chains 24 and 24' are in advance of the chains 25 and 25' to carry the spring elements 28 and 29 in spaced apart relation in accordance with the spacing required to accommodate the number of envelopes for a given size packet. For example, this spacing may be adjusted to accommodate a packet of twenty-five envelopes by moving one or the other sprockets so as to bring the spring elements 28 and 29 sufficiently close together to accommodate twenty-five envelopes therebetween, or they may be moved apart a greater distance to accommodate, for example, fifty envelopes therebetween. With this arrangement, the outer chains 24-24' carry only the spring elements 28, and the chains 25-25' carry the spring elements 29. The spring elements 28 and 29 each preferably constitute flat springs that are fixed at their lower ends to suitable lugs 31 and 32 carried by the respective holders 26 and 27. The spring elements 28 which constitute the front walls of the pockets are slightly bent at their upper ends, as indicated at 33, in the traveling direction of the upper runs of the chains, and are of shorter length than the substantially straight elements 29 that form the rear walls of the pockets. In consequence of this arrangement, the longer spring elements 29 in their advancing movement are able to strike catch mechanisms at the respective sides of the rotor 5.

Each catch mechanism has a stop 35, which may or may not be movable, and a pawl 36 which is under control of the driving mechanism of the machine by means of a reciprocating rod 37. The rod 37 is pivotally connected by a pin 38 with an arm 39 fixed to a rock shaft 40 on which the pawl 36 is supported. The rock shafts 40 are suitably carried by the respective side frames 3. Owing to the continuous travel of the chains, the longer spring elements 29 that form the back walls of the pockets engage the stops 35 and bend backwardly until they slip underneath the stops 35 and the spring action therein flings them into contact with the pawls 36, to be detained thereby. In this way the entrance opening 41 of the pocket to be filled becomes temporarily enlarged and the rotor 5 does not fail to deposit the envelopes therein as long as an envelope is in position on the rotor. The delay just described by the stops 35, in advance of contact with the pawls 36 permits time for the pawls 36 to release the spring elements 29 of the pocket being filled, which release occurs at a predetermined interval, that is, at the moment when the filling of the pocket has been completed. When the outer ends of the spring elements are detained by the pawls 36, the outer ends of the spring elements 28 catch up and make contact with the spring elements 29. The tension of the elements 28 and 29 in cooperation with the pawls 36 is increased by action of the holders 26 being rocked in a forward direction during the advance of the chains of the pocket conveyor. This is effected by cams 42 and 42' (Fig. 5) having cam grooves 43 in inner side faces thereof for engaging pins 44 that extend from the side faces of the pivoted holders. Therefore, as the chains move around the sprockets, the pins 44 enter the cam grooves and pass through a high lobe portion 45 thereof to bring the following spring elements 28 into pressing contact with the spring elements 29 that have been detained by the pawls 36.

As soon as a pocket has been filled with a predetermined number of envelopes, the pawl 36 is moved in a counterclockwise direction (Fig. 3) by pull on the rods 37, whereby both of the detained spring elements 28 and

29 are suddenly released to close the filled pocket and initially open the succeeding pocket. As will be noted in Fig. 3, the added tension of the spring element 28 is brought about by direct contact of that spring element 5 with the element 29, and the corresponding rocking movement of the holder for the spring element 28. As soon as the spring elements are released by the pawls 36, the spring action therein flings them into position shown in Fig. 4, thus terminating the filling of the pocket and starting the opening of a succeeding pocket. By this time, the pawl 36 has been returned to its position where it engages the succeeding spring elements. In this way the action is sufficiently fast for the next envelope to slide into the pocket behind the spring element 28. During this procedure, the spring elements forming the rear wall of the pocket now to be filled are freed from the stop 35 to come into contact with the meanwhile returned pawl 36.

If it happens that the rotor 5 fails to supply the correct number of envelopes, this would result in a faulty filling of a pocket 30. In order to avoid such exigency, a photoelectric cell 46 (Figs. 1 and 2) of any known or convenient type is arranged above the delivery rotor 5. Every time an envelope fails to appear under the cell, the photoelectric cell functions to cause an electric impulse to be transmitted to an intensifier relay 47 (Fig. 2) to energize a solenoid 48 that pushes a pin 49 in a wheel 50 from one side of the wheel to project to the opposite side of the wheel, so that eventually when a faulty packet has arrived at the stacking table 51 of the conveyer mechanism 9, the protruding pin 49 of the wheel 50 makes contact with a switch 52 to establish circuit with an ejector 54 that is operated by an electromagnet 55 to eject that packet and push the faulty packet out of the stack of packets being moved along the table 51. The wheel 50 may be rotatably mounted in any suitable position on one of the side frames and driven in timed relation with movement of the packets of envelopes so that when the faulty packet reaches the place of the ejector, it is discarded.

During movement of the pockets, the envelopes therein are jogged by a suitable vibrating mechanism, as indicated at 56, to register the edges of the respective envelopes preparatory to applying the wrapping band, as now to be described, and which section of the apparatus is best illustrated in Figs. 6 to 9, inclusive.

As a pocket is filled by the rotor 5 at a station designated I, a filled pocket reaches a station II at the delivery end of the pocket conveyer and in a position where the envelopes are lifted out of the pocket by means of the elevator 7. The elevator 7 includes an endless chain 57 operating over upper and lower sprockets 58 and 59 that are carried on transverse shafts 60 and 61. The shaft 60, along with, for example, the shaft 20, is operated in timed relation with the shaft 9 of the wheel 5, so that the conveyer and elevator are in continuous movement with the pocket conveyer advancing at a rate relative to the wheel 5 so that the proper number of envelopes is delivered into each pocket, depending upon the relative spacing of the spring elements 28 and 29 which form the front and rear walls of the pockets. The elevator chain 57 carries at spaced intervals laterally extending arms 62 to engage under a packet of envelopes at the station II, as shown in Fig. 1, and to lift the packet of envelopes upwardly between guide rails 63 and 64.

Just prior to lifting of the packet of envelopes out of the pocket, a strip of wrapping material 65 is pulled from a reel 66 and moved across the path of the packet by feed rollers 67 and 68, a suitable guide roller 69 being provided to change the direction of the strip. The strip 65 is fed between upper and lower grippers 70 and 71 for gripping the strip after a predetermined amount has been fed between knife blades 74 and 75. When the strip is gripped, the knives come into position to sever a sufficient length of strip to extend about the packet of envelopes. The cut off strip thus extends across the path of the packet with

its free end supported on a guide 76, so that as the upward movement of the packet continues, the packet forms a loop in the strip that extends upwardly of the rear face of the packet across the upper edge thereof and downwardly across the forward face, where the end 77 is engaged and held by a downwardly moving suction nozzle 78 having a suction port 78'. The nozzle in its movement presses the free end 77 of the strip downwardly over the front face of the packet while the opposite end is still being held by the grippers, as shown in Fig. 7. The suction nozzle 78 is carried by an arm 79 and moves the nozzle in a direction as indicated by the broken arrow 80 in Fig. 7. At this point a pressure plate 81 is brought into contact with the rear face of the packet by parallel links 82 and 83 to cooperate with the nozzle 78 in holding the packet in compression as the strip is being tensioned therearound. At this point another suction nozzle 84 comes into position to hold the tape in contact with the rear face of the packet while the vacuum through the port 78' is released and the nozzle 78 slides over the free end 77 of the strip as it moves downwardly to its lowermost position below the packet, as shown in Fig. 8. Meanwhile, a strip pusher 85 catches the other end 86 of the strip with release of that end of the strip by the grippers 70 and 71, and moves it underneath the packet and into contact with a gumming segment 87 which is supplied with adhesive from a pickup roller 88 rotatably mounted within an adhesive container 89 that is suitably carried between the frames 3 of the machine. As soon as the gum has been applied, the nozzle 78 begins its return movement and the strip pusher 85 begins its return to its original retracted position, whereupon the gummed end of the strip is re-engaged by the suction nozzle 78, but this time a suction port 90 therein becomes effective to grip the end 86 of the strip and as the nozzle moves upwardly to tighten the strip about the lower portion of the packet and to bring the gummed portion thereof into contact with the other end 77 of the strip, that is, the end being held by the suction nozzle 84. When the suction nozzle 78 has contacted the gummed end 86 of the strip with the end 77, the vacuum through the port 90 is shut off and the pressing face of the nozzle 78 completes the contact. The suction nozzles 78 and 84 and pressure plate 81 now return to their original positions. The wrapped packet continues its upward movement from the banding station III to a drying station IV, which may comprise the drying tunnel 9 in which the adhesive is dried by action of a heating element 91 (Fig. 1), hot air or any other suitable heating medium.

When the wrapped packet reaches a position above the table 51, an oscillatory arm 92 swings into position to move the wrapped packet off the arm 62 of the elevator 7 and onto the table 51 for movement therealong by means of the upper run 93 of the conveyer 10. The conveyer 10 is operated by rollers 94 and 95, so that the upper run 93 thereof extends along the table to carry the wrapped packets in stacked relation to the rear end thereof, where they are removed for boxing.

If the electric eye has previously spotted failure of an envelope to be fed into a packet, the pin actuated by the electric eye is now in position to engage the switch 52 which energizes the electromagnet 55 so that the pusher 54 comes into play and moves the packet off of the conveyer 10.

In the form of the invention illustrated in Fig. 1A, the envelopes are fed from the bottom of a stack 97 that is carried by a stack support 98 onto the upper run of the feed conveyer belt 11. With this type of feed, the envelopes are removed as they are discharged from the envelope making machine and placed in the stack support 98 from where they are delivered to the counting wheel, pocket conveyer and strip wrapping mechanism, as previously described.

The operation of the machine has been set out in the 75

description of the machine, however a brief summary of the operation is as follows:

Assuming that the envelopes are being delivered in successive order from an envelope making machine as shown in Fig. 1, the envelopes pass onto the upper run of the conveyer 11 and between the feed rollers 15 and 16, where they are picked up by the rotor 5 and moved into the first pocket 30 that is moving under the discharge side of the rotor. The pawls 36 have detained the rear spring elements 29 for that pocket and are holding them in open position as the front spring elements 28 continue their forward movement. The envelopes are deposited in the pocket one at a time until the pawl 36 is retracted to release the spring elements 29 of the pocket. Prior to this time the following spring elements 28 of the next pocket were pressing the spring elements 29 so that they snap across the discharge point of the rotor 5 and the next envelope is delivered into the following pocket. Time is allowed for the release of the elements 29 since the stop 35 detains the elements 29 of the following pocket. As the pockets continue their movement, the elements 29 of the following pockets slip from under the stop 35 and are engaged by the pawl 36 until the following pocket has been filled with the required number of envelopes. The envelopes are jostled by the agitator 56 so that the edges thereof are registered in the respective pockets.

Should an envelope fail to appear in position on the rotor 5 below the photoelectric cell 46, a current impulse is passed to the relay 47 to energize the solenoid 48 to cause the pin 49 then registering therewith to be projected from the opposite side of the wheel 50. When the first pack of envelopes reaches the end of the conveyer 6, an arm 62 on the elevator 7 moves under the pack at the station II. Previous to this time a section of the strip 65 has been fed across the upward path of that pack of envelopes so that the free end of the strip is carried on the support 76. The grippers 70 and 71 close on the strip and the blades 74 and 75 operate to sheer off the gripped end of the strip. As the pack is carried upwardly by the elevator, the upper edge of the pack makes contact with the strip and carries it upwardly therewith so that a portion of the strip is carried up the rear face of the pack, across the top edge thereof, and partially down the forward face of the pack, as shown in Fig. 7. The nozzle 78 has now come into contact with the free end 77 of the strip and the vacuum port 78' is effective to engage the end of the strip and pull it down over the pack of envelopes. The vacuum through the port 78' is shut off and the nozzle 78 continues its downward movement relative to the front face of the pack. However, before the free end 77 of the strip is released by the nozzle, the nozzle 84 comes into play to hold the tension on the strip as the nozzle 78 slides therefrom and continues its movement to a position below the upwardly moving pack, as shown in Fig. 8. The pressure plate 81 now comes into pressing contact with the pack to cooperate with the nozzle 78 in pressing the envelopes together. The pusher 85 then comes into play and the grippers 70 and 71 are released so that the pusher 85 carries the free end of the strip 86 under the pack and in position for the end thereof to be engaged by the gum applicator segment 87 to apply gum on the free end of the strip while it is being held by the pusher 85. The adhesive applicator 87 continues its movement 65 past the pusher. The pusher 85 retracts out of the way of upward movement of the nozzle 78. A suction is effected through the port 90 of the nozzle as the nozzle engages the gummed end 86 of the strip, so that the end 86 of the strip is carried upwardly of the forward face of the pack and into lapping contact with the end 77, the pressure of the nozzle being sufficient to effect a seal and completion of the band. The pressure plate 81 having been released, the wrapped packet of envelopes passes freely therefrom and is carried by the elevator 70 through the drying tunnel to a position where it is dis-

charged onto the conveyer 10 of the table 51, as shown in Fig. 1, from where it is removed for boxing.

If a packet of envelopes reaching the table 51 is one containing fewer than the required number of envelopes, the projected pin makes contact with the switch 52 to effect operation of the ejector 54. After contact with the switch 52, the projected pin is returned to retracted position by means of a cam 99 (Fig. 2A).

If the counting and wrapping machine is a separate and distinct machine from the envelope making machine, the envelopes may be removed from the envelope making machine and placed in a stack 97, as shown in Fig. 1A, from where they are delivered onto the conveyer 4.

From the foregoing it is obvious that we have provided for the counting and wrapping of envelopes into packets in a simple and efficient manner and in conformity with the output of a modern high speed envelope making machine.

What we claim and desire to secure by Letters Patent is:

1. In an envelope making machine having a device for delivering finished envelopes in successive order, a conveyer having envelope receiving pockets, means for actuating the conveyer to move said pockets into receiving relation with the delivery device for filling the pockets with envelopes to form packets of a desired size, an elevator at substantially right angles to the conveyer for lifting the packets from said pockets, a wrapping device in the path of the elevator, a reel containing strip material for enwrapping said packets, a pair of feed rollers for feeding the strip material, a cutting device for severing the requisite length of said strip material, grippers for holding one end of the severed strip during enwrapping of a packet, a pressing plate for exerting pressure on said packet at right angles to the elevator, a suction nozzle at the other side of the packet for tightening one end of the strip, another suction nozzle for leading the other end of the strip across to the other side of the packet, means for supplying adhesive to the other end of the strip, said first named suction nozzle being reversible to lift the gummed end of the strip over the one end of the strip and to press and thereby affix the ends of the strip together, and means for discharging the packet from the elevator.

2. Apparatus for banding envelopes into packs, including means containing and supporting a given count of envelopes in a pack, banding means above said pack containing means for applying a tape around the pack of envelopes and securing ends thereof, an elevator having means movable under the pack of envelopes in said pack containing means to lift the pack out of said containing means and to carry the pack through the banding means and to support the pack in continuous movement while the tape is applied to the pack, and means for discharging the banded pack of envelopes from the elevator.

3. Apparatus for banding envelopes into packs, including means containing and supporting a given count of envelopes in a pack, banding means above said pack containing means for applying a tape around the pack of envelopes and securing ends thereof with an adhesive, an elevator having means movable under the pack of envelopes in said pack containing means to lift the pack out of said containing means and to carry the pack through the banding means and to support the pack in continuous movement while the tape is applied to the pack, a drier in the path of the elevator to dry the adhesive, and means for discharging the banded pack of envelopes from the elevator.

4. Apparatus for banding envelopes into packs, including spaced apart front supports for the ends of a pack of envelopes, flexible elements spaced from and co-operating with the front supports in forming a pocket therebetween for containing a given count of envelopes, means for retaining the flexible elements in retracted

position while the envelopes are being inserted into the pocket and for releasing the flexible elements to press the envelopes against the front supports, banding means above the front supports for applying a tape around the pack of envelopes, an elevator having means movable under the pack of envelopes in said pocket to lift the pack in continuous movement through the banding means while the tape is applied to the pack, and means for discharging the banded pack of envelopes from the elevator.

5. Apparatus for banding envelopes into packs, including spaced apart front supports for the ends of a pack of envelopes, flexible elements spaced from and co-operating with the front supports in forming a pocket therebetween for containing a given count of envelopes, means for retaining the flexible elements in retracted position while the envelopes are being inserted into the pocket and for releasing the flexible elements to press the envelopes against the front supports, means for joggling the envelopes in the pocket to register the bottom edges of the envelopes, banding means above the front supports for applying a tape around the pack of envelopes, an elevator having means movable under the pack of envelopes in said pocket to lift the envelopes out of the pocket and to carry the pack in continuous movement through the banding means while the tape is applied to the pack, and means for discharging the banded pack of envelopes from the elevator.

6. Apparatus for banding envelopes into packs, including spaced apart supports for the ends of a pack of envelopes, a continuously movable pack carrying means having portions movable between the supports and under the pack to lift the pack from the supports to carry the pack in continuous movement through a fixed path, means for feeding a tape across the path of the pack to be carried across faces of the outermost envelopes of the pack as the pack is being carried through said path, cutting means for severing a requisite length of the tape to encompass the pack of envelopes, means for gripping the severed end of the tape during continued movement of the pack of envelopes, means extending parallel with said path for exerting pressure on one face of the pack in the direction of said carrying means, a pusher projectable across the retractive side of the pack after release of the gripping means to carry the severed end of the tape across the retractive side of the pack, means cooperating with the pusher for applying adhesive to the end of the tape, a suction nozzle, means for supporting the suction nozzle for substantially reciprocal movement in the direction of movement of the carrying means to engage and pull the free end of the tape over the opposite face of the pack while the pack is being acted upon by the pressure exerting means, a second suction nozzle, means supporting the second suction nozzle for movement into position to engage and hold the free end of the tape while the first named suction nozzle disengages from the tape and moves to the retractive side of the pack to engage the severed end of the tape upon retraction of the pusher and to carry said severed end of the tape with the adhesive thereon into contact with the held end of the tape to connect said ends of the tape, and means for discharging the banded pack of envelopes from said carrying means.

7. An apparatus for banding envelopes into packs as described in claim 6, including a drier between the suction nozzles and the pack discharge means.

8. Apparatus for banding envelopes into packs, including spaced apart supports for the ends of a pack of envelopes, an elevator having arms movable between the supports and under the pack to lift the pack from the supports to carry the pack through a fixed path, means for feeding a tape across the path of the pack to be carried downwardly across faces of the outermost envelopes of the pack as the pack is being carried through said path, cutting means for severing a length of the tape

to encompass the pack of envelopes, means for gripping the severed end of the tape during continued movement of the pack of envelopes, a pusher projectable under the pack after release of the gripping means to carry the severed end of the tape under the pack, means cooperating with the pusher for applying adhesive to the end of the tape, a suction nozzle supported for substantially reciprocal movement with movement of the elevator to engage and pull the free end of the tape downwardly of the opposite face of the pack, a second suction nozzle movable into position to engage and hold the free end of the tape while the first named suction nozzle disengages from the tape and moves to engage the severed end of the tape upon retraction of the pusher and to carry said severed end of the tape with the adhesive thereon into contact with the end of the held end of the tape to connect said ends of the tape, and means for discharging the banded pack of envelopes from the arms of the elevator.

9. Apparatus for banding envelopes into packs, including spaced apart front supports for the ends of a pack of envelopes, flexible elements spaced apart and cooperating with the front supports in forming a pocket therebetween for containing a given count of envelopes on edge, means for retaining the flexible elements in retracted position while a given quantity of envelopes are inserted into the pocket and for releasing the flexible elements to press the envelopes in face to face contact, an elevator having means movable under the envelopes in said pocket to lift the envelopes out of the pocket, means for feeding a tape across the top of the pack lifted by the elevator to be carried across the faces of the outermost envelopes of the pack as the pack is being lifted by the elevator, cutting means for severing a length

of the tape to encompass the pack of envelopes, means for gripping the severed end of the tape during continued movement of the pack of envelopes by the elevator, a pusher reciprocable under the pack after release of the gripping means to carry the severed end of the tape under the pack, means for applying adhesive to one end portion of the tape, a suction nozzle, means supporting the suction nozzle for substantially reciprocal movement in the directional movement of the elevator to engage and pull the free end of the tape downwardly of the front of the pack, a second suction nozzle, means supporting the second suction nozzle for movement into position to engage and hold the free end of the tape while the first named suction nozzle disengages from the tape and moves downwardly to engage the severed end of the tape upon retraction of the pusher and to carry said end of the tape upwardly upon return movement of said first named suction nozzle to bring the end of the tape with the adhesive thereon into contact with the held end of the tape, and means for discharging the banded pack of envelopes from the elevator.
